CLAIM

The ornamental design for a yoke support, as shown and described.

DESCRIPTION

The application is related to co-pending applications: Ser. No. 11/322,837, filed Dec. 30, 2005 and titled “Halo Flex Track”; Ser. No. 11/324,099, filed Dec. 30, 2005 and titled “Halo Power Supplies”; Ser. No. 11/323,231, filed Dec. 30, 2005 and titled “Halo Clam Shell Connections”; and Ser. No. 11/323,755, filed Dec. 30, 2005 and titled “Halo Hubs and Connections”.

FIG. 1 is a perspective view of a first embodiment of a yoke support showing my new design;

FIG. 2 is a side view thereof;

FIG. 3 is a rear view thereof;

FIG. 4 is a top view thereof;

FIG. 5 is a perspective view of a second embodiment thereof;

FIG. 6 is a side view thereof;

FIG. 7 is a front view thereof;

FIG. 8 is a top view thereof;

FIG. 9 is a perspective view of a third embodiment thereof;

FIG. 10 is a side view thereof;

FIG. 11 is a front view thereof; and,

FIG. 12 is a top view thereof.

The broken lines form no part of the claimed design.

1 Claim, 12 Drawing Sheets
